(54) **PRESS, COTTON & HAY, &C.**

(76) Inventor: **Samuel T . Baker**

and useful machine for compressing Hay, Cotton, Hops, Cedar, and all other compressible commodities, and that the following is a full and exact description thereof.

The foundation of the press consists of two sills of about six feet in length, six inches square or any convenient height, to these sills are framed four posts, or plank in an upright position, sufficiently apart as to admit a corresponding box, and of any convenient length, so as to agree with the height of the box, extending about fifteen inches above the same. The box may be made in any convenient manner so as to apply to the commodity to be pressed, or of about eight or nine feet in length or height, three feet eight inches in width, and two feet and one half deep. To the sills are framed two pieces of joist, about five feet and half long in a horizontal manner, connecting the sills to which the lower part of the box is secured at each side. Above these, and one each side, are three pieces of the same dimensions, and at a proper distance from each other, the ends extending through the post, and made fast to the same, and enclose the box at both sides. Inside of the posts, and within eight or ten inches of the same, are framed four pieces of joist, of about the same length, two feet and half long inside the shoulder, and are framed into the aforementioned joist, and enclosing or hooping the box. The box is so constructed as to admit of two followers at the same time, one forcing down & the other up. The doors are in centre of the box on both sides. The doors might be hung at the sides of the box, and secured by iron or wooden bars and hinge. The box has four slips or slides, two at each end so as admit of the foundation of the lower follower to pass up and down. The followers are drawn up and down at the same time, by means of ropes or chains, that are attached to two horizontal shafts. These shafts extend through the upper part of the posts, such a measure as to have the top of the box clear when the upper follower is turned out. The two horizontal shafts produce a reaction when set in motion and are capable of producing double the power that they otherwise would, and destroys the friction, likewise to the ends of these shafts are fixed large blocks of about two feet in diameter or large

or smaller, as the case may require out side of posts, these two cog-wheels match into a pinion that is fast to another wheel, and this wheel matching into another short shaft on which is a pinion, this shaft being set in motion by the large wheel on the side, one end of this lower shaft passes through a perpendicular post, that is secured at the bottom by a side sill, or a small sill that is attached to one of the lower posts, at the top is a piece framed in croppway and secured at each end by the ends of the shaft running through, and are secured by pins, the lower shaft and the ear or shaft of the jockey that matches into the short shaft, the outward ends of the same pass through affix post, and the other ends turn in pieces that are framed across the posts. The upper follower is constructed by framing four pistons upon the follower, at or near the corners of the same across the tops of the pistons, ^{are fast} two pieces of joist of sufficient strength, and extending sufficiently over the shafts so as to receive the ropes or chains in a perpendicular position, to one of these shafts is attached a rope or chain and extending to the follower, and winding the rever to the other rope or chains brings the follower back, and when it is at or near the top of the box, the rope or chains being slipped off from one side, the follower is turned out of the way without trouble. This machine can be made to work with cog, applying them at both sides of the pistons, or slides to draw down, or they may be applied to pistons the advanc or may be attached to the lower follower, and drawing up and down at the same time, or separately with rollers at the back part of the slides, Or to increase the power, there may be the same wheels and pinions attached to the other side or ends of the shafts, and in this way give double the power, or they may be at the end of one shaft one way, and at the other end the other. The cogwheels and pinions to be either of iron or wood.

A machine constructed with this two fold power or the reaction of the one follower upon the other arising from the operation of the one upon the other with ropes, cog or chains, can be made one of the most powerful engines of compression without injury to the machinery.

What I claim as my own invention, and not previously known.

in the above described machine, is the application of the two horizontal shafts in the manner described the reaction they produce in forcing the followers up and down, and the operation of the machine with regard to the double applied power or with the action of one shaft forcing the followers up and down at the same time.
